(57) **CLAIM**

The ornamental design for a stacked shelf cart for storage and transport, as shown and described.

DESCRIPTION

The design of this invention is embedded in a stacked shelf cart for storage and transport.

FIG. 1 is a perspective view of the Multiple Shelf Wagon;
FIG. 2 is a front view thereof;

FIG. 3 is a top plan view thereof;

FIG. 4 is a bottom plan view thereof;

FIG. 5 is a right side view thereof; and,

FIG. 6 is an enlarged cross sectional view, taken along line 6—6 in FIG. 2.

A stacked shelf cart for storage and assembly with four tubular feet or supports having four wheels and two baskets integrally attached to each tubular foot.
